REMOTE-CONTROL FIRING MECHANISM
FOR MACHINE GUNSGeorge R. Oscar, West Milton, and Wayne S.
Boals, Dayton, Ohio

Application April 13, 1942, Serial No. 438,744

1. Claim. (Cl. 89—27)

(Granted under the act of March 3, 1883, as
amended April 30, 1928; 370 O. G. 757)

1

The invention described herein may be manufactured and used by or for Government for governmental purposes, without the payment to us of any royalty thereon.

This invention relates to a trigger-actuating mechanism for firearms and more particularly to a mechanism of this nature which can be controlled at a distance from the firearm concerned.

It is old in the prior art to control the actuation of a trigger of a firearm from a distant point. A device of this nature is shown in U. S. Patent No. 1,352,891, issued to Samuel G. Green on September 14, 1920. According to the disclosure of this patent, a solenoid is secured to the rear end of the gun and a plunger actuated by the solenoid is connected by a linkage to the trigger of the gun. Thus, when the solenoid is energized, the trigger is actuated and the gun caused to fire. It will be noted in the patent to Green, however, that the solenoid is secured behind the pistol grip of the gun, the plunger of the solenoid being connected to the trigger by means of a pivoted lever and a depending link. This arrangement results in the overall length of the gun being increased and necessitates the use of a large solenoid in order to overcome the friction and weight of the lever and link. In order to reduce the bulk and weight of the Green device and, at the same time to simplify the construction, we propose the use of a solenoid which is conveniently arranged so as not to add to the overall length of the gun and which also acts in a direct manner to operate the trigger and cause firing of the gun.

In addition to the arrangement disclosed by Green, it has been common practice to mount the solenoid on the side of a machine gun of the Browning type with the solenoid plunger projected through the side wall of the breech casing and into close proximity to the sear. A cam face provided on the sear and also upon the plunger results in depression of the sear when the plunger is operated and causes the gun to fire. It will be perceived, however, that the placing of the solenoid on the side of the gun increases the overall width of the gun and also causes complications in the construction of the internal mechanism of the breech. In contrast to this sort of an installation, we propose to mount the solenoid on the back plate of the gun where it can actuate the conventional trigger mechanism and where it will not increase the overall width of the gun. It will also be noticed that by mounting the solenoid in this position,

2

a rapid change from manual operation to remote control operation may be effected by merely removing the back plate containing the spade grips and manual trigger and replacing it with one containing the solenoid. In this manner the solenoid is eliminated as a separate mechanism to be attached to the gun and consequently the arming time of the gun is considerably reduced.

Accordingly, one of the objects of our invention is to provide a remote-control trigger-actuating mechanism for a machine gun of the Browning type which mechanism will not increase the overall width or length of the gun.

Another object of our invention is to provide a solenoid controlled firing mechanism which will operate directly upon the conventional trigger mechanism of the Browning machine gun, thereby eliminating the need of any costly revision of the present machine gun structure.

20 A further object of our invention is to provide a remote-control trigger-actuating mechanism for a Browning machine gun in which the mechanism is secured to the back plate of the gun so as to enable ready conversion of the gun from 25 manual control to solenoid control by a mere interchange of back plates.

Still a further object of our invention is to provide a solenoid controlled firing mechanism for a machine gun which is comparatively light 30 in weight and inexpensive to construct. It is possible with our arrangement to use a smaller and lighter solenoid than has been heretofore possible due to the fact that the plunger operates directly upon the trigger mechanism of the gun 35 rather than through a system of links or cams. The weight of our system is further reduced as a result of the elimination of the linkages and camming structures which were formerly interposed between the plunger and the conventional 40 trigger mechanism of the gun.

In the drawing which follows we have shown our improved device mounted on the back plate of a Browning machine gun of the type disclosed in U. S. Patent No. 2,050,539, issued to Frederick 45 T. Moore on August 11, 1936, and U. S. Patent No. 2,108,060, issued to Samuel G. Green on February 15, 1938.

Figure 1 is a side elevation of our device showing how the same cooperates with the conventional machine gun structure, the back plate and breech casing of the gun being shown in cross section in order to better illustrate the invention.

Figure 2 is a rear view of our improved device. In Figure 1 of the drawing, a conventional 55 back plate of the type used with a Browning ma-

chine gun is indicated at 10. This plate may be removed from the gun by sliding it upwardly out of the breech casing, the side plates 12 and 14 of the casing being provided with vertical grooves which receive suitable tenons provided on the back plate. The breech casing is provided with a top plate 16 and a bottom plate 18 so as to completely enclose the breech mechanism and thus protect it from dirt and injury. A sear actuating arm 20 is situated within the breech casing, this arm being pivoted therein in a well-known manner and being adapted to depress the sear when the rear end of the arm is lifted by the trigger. The back plate is latched in place on the rear of the gun by means of a latch 22 pivoted in the back plate at 24. A compression spring 26 urges the latch in a counterclockwise direction about its pivot 24, thus causing a notch 25 formed in the latch to engage with the rear edge of the bottom plate 18. To remove the back plate it is only necessary to release the latch 22 and slide the plate upwardly out of the gun.

To the back plate 10 is secured the well-known buffer tube 28 on the top of which is mounted a solenoid 30 by means of straps 32 and clamping bolts 34. In order to insure that the solenoid will not be jarred out of position during firing of the gun, a forwardly extending flange 36 on the solenoid is received between spaced flanges 32 provided on the back plate 10 secured thereto by means of rivets 40. A spring-retracted plunger 42 is located within the solenoid and is provided with an extension 44 which engages the rear face of a trigger 46 pivoted at 47 in a recess cut in the back plate. This trigger is normally urged in a clockwise direction by means of a compression spring 48 so as to insure the release of the sear actuating arm 20 by the trigger when the solenoid is deenergized. The extension 44 is threaded at one end and screws into a tapped hole extending longitudinally into the end of plunger 42. A nut 49 screwed onto the extension 44 provides a means for adjustably securing the extension in the end of the plunger 42. By means of this adjustment the position of the trigger with respect to the sear actuating arm when the solenoid is deenergized may be adjusted as desired. A conductor 50 is connected to the solenoid for supplying the energizing current thereto so as to enable the solenoid to expel the plunger 42 against the trigger 46, thus swinging the trigger in a counterclockwise direction about its pivot 47 so as to cam up the end of the sear actuating arm 20.

If desired, a manual means for firing the gun may be supplied in addition to the solenoid, this means taking the form of a bell crank 52 (see Fig. 2), which is pivotally mounted at 54 on a bracket

56 which is clamped to the rear end of the buffer tube 28 by a bolt 58. One arm of the bell crank 52 is provided with a thumb plate 60, the other arm 62 being provided at its upper end with a dog 64. The dog 64 is pivoted to the arm 62 at 66 and may be moved to either an effective or ineffective position for actuating the plunger 42. As shown in Figure 1, the dog is in its effective position with the projection 68 thereon in position to contact the rear end of the plunger 42 and move the plunger to the right when the thumb plate 60 is depressed. The dog 64 is held in the position shown in Figure 1 by means of a spring-loaded ball detent located in a recess in the arm 62 (not shown). If it is desired to render the manual operating means ineffective, the dog may be moved ninety degrees counterclockwise from its Figure 1 position where it will be retained by the detent. In this position of the dog, the projection 68 will be ineffective to actuate the plunger 42 upon depression of the thumb plate 60. The bell crank 52 is provided with a torsion spring 70 which normally retains the bell crank in its counterclockwise, or Figure 1, position.

From the above description and the accompanying drawings it will be seen that we have provided a solenoid trigger-actuating mechanism which may be operated from a distance to effect the firing of a machine gun. It will also be observed that the solenoid is so mounted on the rear of the gun that it may act directly upon the conventional trigger mechanism thus dispensing with any intermediate linkages. It will further be seen that by securing the solenoid directly to the back plate of the gun it is possible to change over from a remotely controlled firing system to a manual one by a simple interchange of back plates. The extreme simplicity and desirability of our device as compared with the prior art devices is readily apparent from the drawing and the foregoing description.

What we claim as new and desire to secure by Letters Patent is:

For use with a machine gun, a fire control device comprising a back plate, a buffer tube secured to said back plate, a trigger pivotally mounted on said back plate, a solenoid for electrically operating the gun, means for clamping said solenoid to said buffer tube, a plunger of extensible length within said solenoid aligned with said trigger so as to cause the gun to be fired when the solenoid is energized and permanently locked means secured to said solenoid and to said back plate for locating and holding said plunger in alignment with said trigger.

GEORGE R. OSCAR,
WAYNE S. BOALS.
